SEWING MACHINE

Albert Kadden, New York, N. Y., and Minoru Arai,
Sakai, Osaka, Japan, assignors to S. K. S. Machine
Company, New York, N. Y., a corporation of New
York

Application January 23, 1957, Serial No. 44,572

Term of patent 14 years

(Cl. D70—2)

The figure is a perspective view of the sewing machine.

The dominant features of the design are shown in full lines in the drawing. The elongated cutout portion in the front of the top of the sewing machine is considered to be a particularly dominant feature. The other side and back of the machine, not shown in the drawing, are considered to be conventional.

We claim:

The ornamental design for a sewing machine, as shown and described.
